UNITED STATES PATENT OFFICE.

HENRY W. LEWIS, OF WASHINGTON, DISTRICT OF COLUMBIA.

WORK-BENCH.

1,218,193.

Specification of Letters Patent.

Patented Mar. 6, 1917.

Application filed April 6, 1916. Serial No. 89,433.

To all whom it may concern:

Be it known that I, HENRY W. LEWIS, a citizen of the United States, residing at Washington, in the District of Columbia, have invented certain new and useful Improvements in Work-Benches, of which the following is a specification.

My invention relates to work benches and has for its object the provision of simple and inexpensive means whereby a board may be properly held during the operation of planing or sawing. One object of the invention is to provide a holder or support for the work which may be readily adjusted to insure the planing of a board to the proper depth, and another object of the invention is to provide novel means whereby boards of different widths may be accommodated and held steady during the operation of sawing. The invention is illustrated in the accompanying drawings and consists in certain novel features which will be hereinafter first fully described and then more particularly pointed out in the claims following the description.

In the drawings:

Figure 1 is a perspective view showing my improved work holder in position upon a bench;

30 Fig. 2 is a bottom plan view of the holder;

Fig. 3 is a longitudinal section on the line 3—3 of Fig. 2;

Fig. 4 is a transverse section on the line 4—4 of Fig. 3;

35 Fig. 5 is a detail perspective view of the means for varying the height of the platform upon which the work rests;

Fig. 6 is a detail section taken through the plane of the pivot by which the work rest or platform is connected with the frame.

The work bench 1, shown in the accompanying drawings, may be of any desired dimensions or construction and will ordinarily be equipped with a vise 1^a as is well known.

In carrying out my invention, I employ a frame consisting of side bars 2 and 3 connected at one end by a cross bar 4 and at intervals between their ends by braces 5. The side bar 3 is of greater vertical dimension than the side bar 2 so that, if the rear bar 2 and the end bar 4 be placed upon the surface of the work bench 1, the front side bar 3 will bear against the front edge of the

bench and abut the inner fixed jaw of the vise 1^a, as clearly shown in Fig. 1. The upper edges of both side bars 2 and 3 are inclined downwardly from the end bar 4 toward the free ends of the side bars and in the said upper edges of the side bars, immediately adjacent the end bar 4, I provide a stepped series of notches 6 which are adapted to receive a gage bar or rest 7. This gage bar or rest consists of a single bar of proper length to seat in corresponding notches in the two side bars and provided at its ends with downturned portions or stops 8 adapted to engage against the outer surfaces of the side bars and thereby prevent endwise movement which would release the gage from the notch. The frame will preferably be constructed of metal and may conveniently be cast in one structure and the rest or gage 7 may be of metal or of wood, as may be preferred. A stop bar 9 is fitted between the side bars immediately adjacent the end bar and this stop bar will preferably be of wood so that the blade of a plane will not be injured by contact therewith. The stop bar 9 is provided with a lip or flange 10 along one side which rests upon the upper edge of the end bar 4 and thereby supports the said stop bar in its operative position. A platform or rest 11 is disposed between the side bars 2 and 3 and is pivoted to and between said side bars by a pintle member 12 having trunnions 13 at its ends engaging suitable openings in the side bars, as shown most clearly in Fig. 6. This platform or rest 11 has cleats 14 secured to its under side so as to counteract a tendency to warping or splitting and also reinforce the platform, as will be readily understood. The free end of this platform is supported by the gage bar 7, as shown clearly in Fig. 3, and the said platform will assume various inclinations, accordingly as the said gage is seated in one or another of the notches 6. When the gage 7 is seated in the lowest notches, a board 15 placed upon the platform or rest 11, with one end bearing against the cushion or stop 9, will project very slightly above the said stop 9 but, if the gage be set in the higher notches, the platform will, of course, be swung upwardly about its pivot 12 and the free end thereof will, consequently, be raised relative to the stop 9 so that a board placed upon the plat-

form will project to a greater extent above the said stop. The platform or work holder can thus be very easily and quickly adjusted so that the work will project above the stop 9 to the exact extent to which it is to be planed.

When the board to be planed is of even straight grain wood, it will be held sufficiently steady by having one end in contact with the stop 9 but, if the wood be cross-grained, it will frequently tend to swing around as the plane is moved over its surface and render the operation laborious and difficult. To resist this tendency, I provide an additional stop 16 consisting of a bar disposed longitudinally of the work holder and adjacent the rear edge thereof or side bar 2. This stop 16 is preferably a wooden strip secured to a metallic bar 17 which is carried by the upturned ends of rack bars 18, the use of a wooden bar avoiding injury to the tools, as will be readily understood. The rack bars 18 are disposed below the platform 11 and play in transverse housings or guides 19 which may be of tubular or other formation, provided the end immediately adjacent the side bar 2 is sufficiently large to furnish the necessary clearance to permit the rack bars to play through and engage the lower walls of the notches 20 formed in the said side bar. When the notches in the lower edges of the rack bars 18 engage the edges of the notches 20 in the side bar 2, as shown in Fig. 4, the rest or stop 16 will be held in a fixed position relative to the platform 11 but, if the said stop be raised sufficiently to permit the rack bars to clear the bases of said notches, the device may be shifted transversely of the platform so as to move the stop 16 toward or from the platform and thereby set the device for boards of various widths. The stop 16 also serves as a gage to guide a saw when a board placed upon the platform or work holder is to be sawed. If the board is held against the member 16 with one end thereof projecting beyond the said member so that the point at which the kerf is to be formed will be in alignment with the end of the stop, the saw may be readily operated to cut a straight kerf at the desired point if the side of the saw be held against the end of the stop, as will be readily understood.

From the foregoing description, taken in connection with the accompanying drawings, it will be readily understood that I have provided an exceedingly simple and inexpensive device whereby the work may be firmly supported and quickly set so that the extent to which it will be planed will be determined without constantly measuring the same as the work progresses. The device is especially adapted for use in training schools where the pupils are not proficient in the use of tools and through their lack of

skill frequently destroy valuable tools and material. The platform or rest 11 may be quickly changed from one inclination to another by merely raising the free end of the same, shifting the gage bar 7 and then lowering the platform, as will be readily understood, and should the stop 9 become broken or damaged through long continued use or through accident, so that its efficiency is destroyed, a new stop member may be provided in a few minutes. This member is not secured to the frame but merely rests on the end bar of the same between the side bars and, when in use, will be held against movement by the side bars of the frame and by the work pressing it against the end bar. The racks 18 may be easily adjusted and, when in use, will be held steady and firm by reason of the bottoms of the guides being inclined upwardly from the side bar 2 to the front side bar 3, as shown most clearly in Fig. 4. As the said members are adjusted toward the front side bar 3, the greater weight of the same will tend to cause the front ends thereof to drop, but this tendency is overcome by the said ends engaging against the bottoms of the guides.

Having thus described my invention, what is claimed as new is:

1. In a device for the purpose set forth, a frame comprising side bars and cross bars connecting the same, the front side bar depending below the plane of the rear side bar whereby the frame may rest upon a bench with the front side bar abutting the front edge of the bench, a platform pivoted to the frame at one end thereof, and an adjustable support for the platform at the opposite end of the frame.
2. In a device for the purpose set forth, the combination of a frame, a platform pivoted to the said frame at one end thereof, a support for the free end of the platform adjustable upon the frame, and a stop on the frame adjacent said support and beyond the free end of the platform.
3. In a device for the purpose set forth, the combination of a frame, a platform pivoted at one end in the frame and adjustably supported thereon at its free end, a transverse stop on the frame adjacent and rising above the free end of the platform, and a longitudinal stop adjustable transversely of the frame and rising above the rear edge of the platform.
4. In a device for the purpose set forth, the combination of a frame comprising side bars provided with stepped notches in their upper edges adjacent one end, a gage bar adapted to seat freely in the said notches and provided at its ends with depending stops adapted to engage the outer faces of the side bars, whereby to be held against movement transversely of the frame, and a platform pivoted at one end to and between

the side bars and having its free end extending over and resting upon said gage bar.

5. In a device for the purpose set forth, the combination of a frame, a platform pivotally supported at one end of the frame, an adjustable support for said platform at the opposite end of the frame, the frame being

provided with notches in its rear side, transverse guides upon the frame, racks playing in said guides and engaging the bases of 10 said notches, and a longitudinally disposed stop carried by the rear ends of said racks.

In testimony whereof I affix my signature.
HENRY W. LEWIS. [L. S.]
